United States Patent Office.

ROBERT HITCHCOCK, OF SPRINGFIELD, MASSACHUSETTS.

Letters Patent No. 96,114, dated October 26, 1869.

RAILROAD-CAR VENTILATOR.

The Schedule referred to in these Letters Patent and making part of the same.

To all whom it may concern:

Be it known that I, ROBERT HITCHCOCK, of Springfield, Hampden county, Commonwealth of Massachusetts, have invented a new and useful Improved Car-Ventilator; and I do hereby declare that the following is a full and exact description thereof, reference being had to the accompanying drawings, and to the letters of reference marked thereon.

In the drawings—

Figures 1, 2, and 3, represent different views of my invention, the same parts being lettered similarly throughout.

This invention consists in arranging a ventilator for cars, which will send through the latter a constant supply of fresh air, but does not allow the cinders and trash to pass in with it.

To accomplish this, I form my ventilator as I will now describe.

A is a sheet-metal case, which has openings at both ends, forming a tunnel for the air to rush through as the train moves along, this case being placed upon the top of the car, longitudinally parallel with it.

The sides of this case A are double, leaving a chamber all around the central tunnel B, except at the ends, which are bevelled from the edge of the outer shell to the inner, at the top and sides, so as to form a funnel at each end, for the purpose of more completely catching the breeze.

In the top of the tunnel B is a door, G, which is cut through into the surrounding chamber.

The supply-pipe C, communicating with the car, enters the bottom side of the case A, passing through the outer shell, and projecting somewhat above it, but not reaching to the bottom plate of the tunnel B.

Close to each opening of the latter are swung two gates, E and F, which are acted upon by the current of air passing through the passage B. These are hinged at the upper side of the same, swinging free at the bottom, but may be weighted at the top, so as to balance them, and render them susceptible to the slightest breath of air.

Stops a', &c., are placed upon the sides of the tunnel, to regulate the play of these doors. It will be seen that these stops are arranged to give the doors much more swing inside than outward. This is for the purpose of gathering the air and forcing it up through the hole G, while at the same time sufficient current is left at the bottom of the tunnel B to

carry through the cinders, whether they pass directly through or are deflected by the front door.

In order to provide, however, for the possibility of any trash getting into the inside case, I place at the bottom side of the outside shell, at each end, a number of slots, c d e, &c., which would permit the trash to escape through them.

If it should be desired, wings could be attached on the sides of the openings to the tunnel, on both ends, so as to catch more air.

By this means, I obtain a ventilator which supplies a constant stream of fresh air, but completely sifts the same of all foreign matter, which would otherwise intrude itself with the draught.

In very cold weather, when a mere suction of air would be sufficient, I remove the outside stops at each door, so that both doors blow aside, allowing the current of air to pass directly through the tunnel, the front door still, however, deflecting the cinders from the opening at the top.

In the drawings, at fig. 3, is shown another method of applying my ventilator. In this case, the case A is attached to the side of the car, the air passing up through the opening G, and through the supply-pipe C, which in this case is on one side, and not at the bottom. Cinders which might accidentally get into the inside shell are allowed to fall out through slots in the lower part of the case at K. This may prove more convenient in adapting my invention to certain classes of cars which are built with a raised central roof.

Now, having described my invention,

What I claim as new, and desire to secure by Letters Patent, is—

1. A car-ventilator, having the case A, formed with the direct passage B through it, and the double walls, and having the opening G through the top of the passage B, through which air is forced, so as to pass around through the hollow sides, and through the supply-pipe, the parts being arranged substantially as shown.

2. In combination with the above, the balance-doors E and F, arranged with stops a', &c., substantially as herein shown.

ROBERT HITCHCOCK.
